UNITED STATES PATENT OFFICE

2,299,644

SIGNAL RETRANSMISSION SYSTEM

Manfred W. Muehler, Nutley, N. J., assignor to
American District Telegraph Company, Jersey
City, N. J., a corporation of New Jersey

Application July 12, 1939, Serial No. 283,938

2 Claims. (Cl. 177—367)

This invention relates generally to signaling systems adapted to transmit signals from a subscriber's station to a central office for the purpose of reporting fire conditions, burglaries and the like. The system embodying this invention pertains more particularly to central office signaling systems wherein it is desired to retransmit a subscriber's signals to police or fire headquarters for the purpose of expediting effective response to the various types of alarms.

The conventional signaling system used for transmitting fire and burglary alarms to a central office comprises subscribers' stations adapted to transmit signals by both grounding and interrupting the line circuit in either side thereof, the signals being received at the central office by means of relays connected to either side of the line and battery or ground. This system is more generally known as the McCulloh circuit.

In accordance with this invention, the subscribers' signals are transmitted to the central office in the conventional manner but in order to economically utilize existing line facilities, it is found advantageous to retransmit the subscribers' signals over the same subscriber's circuit to one or more headquarters stations. In accomplishing this result, it is necessary that all signals should be received in spite of grounds or breaks in the transmission line and it is further necessary that retransmission be possible without interference with subscriber's signals being transmitted to the central office.

Accordingly, the principal object of this invention is to provide a system for the retransmission of either police or fire alarm signals to one or more headquarters receivers over the conventional McCulloh circuit.

Another object of this invention is to provide a signaling system for retransmission to police or fire headquarters of a subscriber's signals over the subscriber loop without interfering with the reception of other subscribers' signals.

It is a still further object of this invention to retransmit fire or police alarm signals to the proper headquarters stations without interfering with the receiving function of the relays within the McCulloh circuit.

Still another object of this invention is to provide, in a fire or police alarm circuit, retransmission of subscriber's signals from the central office to the headquarters stations in spite of breaks or grounds in the transmission line.

Further objects of this invention will be apparent to those skilled in the art from an inspection of the specification taken in connection with the accompanying drawing wherein:

The single figure of the drawing is a circuit diagram of a retransmission system for use in a McCulloh circuit.

The signaling system embodying the inven-

tion comprises a plurality of subscribers' stations 1 connected in both sides of the transmission line 2 which extends between a number of headquarters stations indicated in the drawing as 30 and 60 and a central office comprising the usual McCulloh receiving relays 3. Patent No. 253,080, issued to C. F. McCulloh on January 31, 1882, shows a suitable central office circuit for use in the applicant's system. So far, the system as described includes the essential elements of the McCulloh signaling system described in detail in the above-mentioned patent with the exception of the headquarters receiving stations. In order to retransmit signals received at the central office, it is necessary to provide a transmitter 10 which may be either manually or automatically operated in accordance with the received signals. For example, the transmitter shown in Patent No. 907,600 issued to R. M. Hopkins on December 22, 1908, is suitable for such purposes. Transmitter 10 interrupts the circuit from battery 11 to repeating relay 14 and thereby generates signals for retransmission. A recorder 16 is connected across battery 11 and contact 15 of relay 14 for the purpose of locally providing a record of the retransmitted signals.

To obtain retransmission of signals without interference with subscriber's signals, an alternating current source 24 is connected to contacts 18 and 19 of relay 14 through the transformer 22 and condensers 25 and 26 whereby relay 14 keys the alternating current to transmit signal impulses to the transmission line 2 and headquarters stations 30 and 60. The choke coils 4 are connected between receiving relays 3 and transmission line 2 for preventing actuation of these relays by the alternating current impulses transmitted from contacts 18 and 19 while the condensers 25 and 26 prevent flow of direct current through the transformer 22 to ground.

The retransmitted signals are received at the headquarters stations and operate relays 33 and 34 which in turn operate the repeating relay 40 to control the recorder 45. The condensers 36 and 37 prevent the flow of direct current through the receiving relays 33 and 34 and at the same time pass the retransmitted alternating current signals. The choke coil 35 shunts relays 33 and 34 to allow the flow of direct current through the transmission circuit 2 and at the same time prevents the alternating current impulses from being shunted around relays 33 and 34. The relay 40 includes a short-circuited winding 41 located at the armature end which introduces a delay characteristic in the performance of this relay to prevent actuation thereof by direct current charges within the condensers 36 and 37 which build up as a result of the normal direct current potential of the closed subscriber's loop.

existing between battery and ground. Thus when a subscriber's transmitter operates, the condensers discharge through the ground circuit and sometimes momentarily operate relays 33 and 34, but the delay characteristic of relay 40 prevents its actuation.

The bell 46 is provided for the purpose of calling the attention of the headquarters operator to the recording of signals in recorder 45.

The headquarters station 60 is similar in all respects to station 30 and therefore only the line connections are shown in the drawing for the purpose of indicating the manner of connecting a plurality of such stations. The choke coil is not connected at intermediate headquarters stations since it is unnecessary.

The operation of the system is started at the subscriber's stations indicated by the numeral 1 on the drawing which alternately ground and break the transmission line 2 thereby alternately operating the central office relays 3 from battery 5. The relays 3 operating in accordance with the system described in the above cited patent cause a record to be made of the subscriber's signal which may then be manually or automatically set up in transmitter 10. This transmitter breaks the circuit from battery 11 to relay 14 in the obvious manner to operate the contacts 15, 18 and 19. Contact 15 breaks the circuit from battery 11 to the recorder 16 to provide a local record of retransmitted signals. The contacts 18 and 19 impress alternating current voltage on both conductors of the transmission line 2 in accordance with the signals generated at transmitter 10. Thus a circuit may be traced from one side of transformer 22 through condenser 25, contact 18 of relay 14 over one side of transmission line 2 and through the subscriber's stations, condenser 36 and relay 33 to ground. The contact 19 of relay 14 closes an obvious circuit over transmission line 2 to relay 34 at the headquarters station 30. Either of the relays 33 and 34 operating in series and closing their contacts, puts battery on relay 40 which repeats the retransmitted impulses to recorder 45 through an obvious circuit.

If a subscriber's station is operating in one side of the line to apply breaks and grounds to the transmission line, the retransmitted signals being applied to both sides of line 2 may still operate one of the relays 33 or 34 through the ground circuits. Thus the operation of a subscriber's station or a plurality of them in one side of the line 2 does not prevent retransmission of signals to the headquarters stations. Choke coils 4 prevent interference between alternating and direct current signals at the McCulloh panel. If the ground at any of the headquarters stations becomes faulty, retransmission is carried on over both sides of transmission line 2 in series. This is possible because the E. M. F. in one half of the secondary winding of transformer 22 is opposite in phase to that of the other half of the secondary.

From the above description of the system it is evident that subscribers may transmit their fire or police alarm signals over either side of the McCulloh circuit in the conventional manner, while the central office attendant may retransmit these signals to the police or fire headquarters over the subscriber's loop circuit without interfering with the subscriber's circuit or the central office equipment. If the one side of the transmission line is broken or grounded, either through

faults or subscriber operation, the signals are retransmitted over the other side of the line. Or if a ground connection at the central office or the headquarters is faulty, the signals may still be transmitted through a series circuit to the headquarters' receiving relays.

Although only one modification of this invention has been described, it will be obvious to those skilled in the art that this invention is capable of several modifications and therefore applicant desires that the invention shall be limited only by the prior art and the extent of the appended claims.

I claim:

1. In a signalling system, a transmission line including a plurality of subscriber's stations and a plurality of headquarters stations therein, a central office connected to said transmission line including a direct current source and receiving relays connected to each side of said transmission line for receiving direct current signals from said subscriber's stations, a transmitter at said central office for retransmitting the subscriber's signals, a transmitting relay connected to said central office transmitter and having contacts connected to each side of said transmission line for keying it, an alternating current source connected between each of said contacts and ground, choke coils connected to each of said receiving relays for blocking alternating current signals transmitted from said central office transmitter and passing direct current signals from said subscribers' stations, a pair of receiving relays connected between each side of said transmission line and ground at each of said headquarters stations, condensers connected in each side of said transmission line for blocking direct current signals from the subscribers' stations, a repeating relay at each of said headquarters stations responsive to either or both of said receiving relays and having a delay characteristic rendering it non-responsive to direct current charges on said condensers and a signal receiver at each of said headquarters stations responsive to said repeating relay for indicating signals received over either or both sides of said transmission line.

2. In a signalling system, a transmission line including a plurality of subscribers' stations for transmitting direct current signal impulses, a central office connected to said transmission line including receiving relays connected to each side thereof for receiving signals from said subscribers' stations, a plurality of headquarters stations connected in said transmission line, a transmitter at said central office for retransmitting the subscribers' signals to the headquarters stations by means of alternating current signals over either or both sides of said transmission line, means at said central office for blocking the alternating current signals from said receiving relays and passing direct current signals from said subscribers' stations, a pair of receiving relays connected between each side of said transmission line and ground at each of the headquarters stations, condensers connected in each side of said transmission line for blocking direct current signals from said subscribers' stations and a receiver at each of said headquarters stations responsive to either or both of said receiving relays for indicating signals received over either or both sides of said transmission line.

MANFRED W. MUEHTER.
